UNITED STATES PATENT OFFICE.

EZRA O. GARLAND, OF NEW BEDFORD, MASSACHUSETTS.

VAPOR-BURNER.

SPECIFICATION forming part of Letters Patent No. 251,709, dated January 3, 1882.

Application filed September 30, 1881. (No model.)

To all whom it may concern:

Be it known that I, EZRA O. GARLAND, of New Bedford, county of Bristol, and State of Massachusetts, have invented an Improvement 5 in Vapor-Burners, of which the following description, in connection with the accompanying drawings, is a specification.

My invention relates to vapor-burners for hydrocarbon fluids.

10 In burners of this class as heretofore commonly constructed the liquid passes through a suitable passage to a small orifice, where it is ignited, the said fluid being converted to a vapor by the heat of the parts after the flame has been burning a short time. This orifice is usually controlled by a needle-valve mounted on a screw-threaded stem, so that by rotating the said stem the point of the needle is caused to move through the orifices for the purpose 15 of clearing it when it becomes clogged or for partly closing it to control the effective area of the orifice and consequent size of the flame. By this arrangement a considerable rotary movement of the valve-stem is required to 20 produce an effective longitudinal movement of the point of the valve, and the process of clearing the orifice of the burner is consequently a slow one.

This invention has for its object to give the 25 needle-valve a direct reciprocating movement, and at the same time to enable it to be fixed in any desired position so as to properly regulate the passage of the fluid. The needle-valve is mounted in a carrying-block, which is 30 guided by and free to slide in a tubular passage, and an operating-handle is properly connected therewith to give the said block and connected valve the desired sliding movement. A clamp is provided by which the said operating-handle and connected valve may be fixed 35 in any desired position to control the passage of the fluid, and thereby regulate the flame.

Figure 1 is a vertical section of vapor-burner constructed in accordance with my invention; Fig. 2, an elevation thereof, as viewed from the right-hand side of Fig. 1, the socket of the operating-handle being shown in section; Fig. 3, a section on line $x-x$, Fig. 2, illustrating the holding-clamp for regulating the 40 burner; and Fig. 4, a side elevation of the valve and its carrying-block detached.

The burner a , with its inlet-passage b and orifice c , may be of any usual construction. Below the burner and in line with the passage leading directly to the orifice is a tubular 55 guide, d , which receives a block, e , carrying the needle-valve f , adapted to clear and control the orifice c , the said valve-carrying block e being of suitable material to slide easily in the guide-tube d . The said guide-tube d is 60 provided with a tubular projection, g , extending laterally from the part occupied by the block e when in an intermediate position. The socket h for the valve-operating spindle i projects laterally from the projection g , and is 65 screw-threaded internally.

The valve-operating spindle i is shown as a threaded rod having a portion, j , bent at an angle to the threaded spindle to serve as a handle to enable the latter to be easily rotated. 70 The said spindle i is so connected with the block e that a slight rotary movement of the said spindle will produce a longitudinal movement of the needle f toward or from the orifice c , which may thus be thoroughly cleared by a 75 slight oscillation of the handle j . As herein shown, the block e is provided with a notch or hole, 2 , and the handle i is provided near its end with a hole, 3 , which, when the said handle is in place in its socket, as shown in Fig. 80 2, lies within the tubular projection g and opposite the said notch 2 . A pin, l , is passed through the hole 3 and enters the notch or hole 2 , as shown in Fig. 1, the end of the projection g being left open to enable this pin to 85 be inserted. When the parts are thus properly put together by screwing the spindle i into its socket and inserting the pin l the end of the projection g is closed by a screw-plug, m , which serves also to retain the pin l in 90 proper position.

The end of the handle-socket h is split on one side, as shown at 4, Fig. 3, to form a clamp, which is operated by the thumb-screw n to tightly hold the handle i and fix the point of 95 the valve f in any desired position to properly regulate the flame.

The handle i is screw-threaded for the purpose of packing, as its longitudinal movement is immaterial; and it will be seen that by making the valve containing tube and handle-socket in a single piece, as herein shown, the 100

burner is as tight at every point as when provided with the usual threaded stemmed valve.

I claim—

1. The guide-tube, lateral projection there-

5 from, and handle-socket extending laterally from the said projection, all made of a single piece, combined with the needle-valve and its carrying-block fitted in the said guide-tube, and the valve-operating handle mounted in

10 the said socket, and connected with the said block, to operate it and the connected valve, substantially as described.

2. The guide-tube, tubular projection there-

15 from, and handle-socket, combined with the valve and its slotted or notched carrying-block

and the handled spindle, and pin mounted therein and entering the slot of the valve-car-

rying block, substantially as described.

3. The reciprocating needle-valve and its

20 carrying-block, and the valve-operating handle

connected with the said block, combined with the handle-socket slotted and pivoted with a clamping-screw to fix the said handle and valve in any desired position, substantially as de-

scribed.

4. The valve and guide-tube and lateral

tubular projection therefrom and the handle-

socket, combined with the valve-operating

handled spindle and pin to connect it with the

said valve, and the screw-plug to close the

30 end of the said tubular projection and retain

the said pin in proper position, substantially

as described.

In testimony whereof I have signed my name to this specification in the presence of two sub-

35

scribing witnesses.

EZRA O. GARLAND.
